UNITED STATES PATENT OFFICE

HAROLD H. MIRKIL, OF PHILADELPHIA, PENNSYLVANIA

BLOCK PRINTING MACHINE

Application filed January 17, 1930. Serial No. 421,357.

My invention relates to improvements in block printing machines, and relates especially to improved means for reciprocating the paint wagons relatively to the printing surfaces of the blocks.

The object is to provide improved means, operating relatively to the reciprocating movements of the blocks, for communicating reciprocating movement to the paint wagons, which shall be simple in construction and accurate in operation, and which shall give acceleration and retardation of said reciprocating movements as required, to effectually prevent shocks and jars and to prevent uncontrolled movement or lost motion; that is, so as to secure a gradual starting and stopping of said reciprocating movements and to secure the required dwell of the wagons for proper cooperation with the printing blocks.

Referring to the drawing which illustrates merely by way of example a suitable embodiment of the invention:—

Fig. 1 is a side elevation.

Fig. 2 is a horizontal section on line 2, 2 of Fig. 1.

Similar numerals refer to similar parts throughout the several views.

In the example shown in the drawing the wagons 7 are provided with wheels 8 running on track 9 and connected together by the links 10 in the usual way. At each end of the train of cars a longer link 11 is connected from the last car 7 to the lever 12 mounted onto shaft or other suitable bearing 13, associated with the framework of the machine. This lever 12 is preferably bifurcated at its lower end, and between the two parallel arms thereof are suitably mounted the rollers 14 and 15. These rollers cooperate with the peripheries of the cams 16 and 17 respectively. These cams 16 and 17 are mounted on the shafts 18 and 19 journalled in the framework of the machine and are provided with the gear wheels 20 driven by the pinion 21. The pinion 21 is mounted on shaft 22 driven through suitable gears, synchronously with the cams 23, which operate the printing heads or blocks 24. These printing blocks 24 are operated in the usual way with a dwell in the elevated position for receiving the pigment or paint from

the paint wagons, and a dwell in the depressed position for the printing operation. The wagons are reciprocated across the path of travel of the blocks, with a dwell between their movements in opposite direction to allow for the up and down movements of the blocks. It is essential that the paint wagons shall be moved beneath the printing blocks so that the rollers may transfer the paint to the printing surfaces of the blocks as quickly as possible after the blocks come into position to receive the pigment, and that the blocks shall start to move downwardly as promptly as possible after the rollers have transferred the pigment thereto. For this reason the actuations of the blocks and of the wagons should be precisely and closely coordinated.

It is also important that the actuation of the wagons shall be such as to cause gradual retardation prior to the period of dwell and gradual acceleration after the period of dwell so that the main reciprocating movements may be relatively quick without undue agitation of the pigment in the wagon or uneven distribution of the pigment upon the printing surface of the block.

It may also be desirable to have the wagon move with constant speed while the roller is in contact with the block.

It is also important that the reciprocating movements of the wagons shall be precise and definite without lost motion or vibration, as this tends to disturb the proper distribution of the pigment on the block.

To secure these objects I provide the cams 16 and 17 rotating in the same direction on parallel axes on opposite sides of the lever 12 and cooperating with the rollers 14 and 15 suitably mounted on said lever 12. These cams are provided with short extensions as 26 and 27 which are in the arcs of the axes of the cams, so that there is a dwell with every half rotation of the cams, and between each dwell the lever is moved either to the right or left to carry the wagons beneath the printing blocks for the transfer of pigment, and between the dwells the cam formations are such as to cause a gradual starting and stopping movement of the lever 12 and hence of the wagons. As both

cams are always in engagement with their cooperating rollers the actuation of the lever is positive and there is no possibility of free play or lost motion between the lever 5 and its actuating mechanism, at least except by possible wearing of the bearings, and to obviate possibility of such event, special bearing bushings are provided, especially for the rollers 14 and 15, which may be

10 changed from time to time as required.

It will be obvious that by the proper formation of the contours of cams 16 and 17, which always move synchronously with the block actuating cams 24, the desired coordination of actuation of blocks and paint 15 wagons may be secured with absolute precision.

What I claim is:—

In a block printing machine using reciprocating paint wagons, means for operating 20 said wagons, comprising a pair of oppositely disposed cams rotating on axes on the same horizontal plane, a reciprocating lever having its axis parallel with the axes of the cams 25 but below the said horizontal plane thereof, a pair of rollers journaled on opposite sides of the lever between its axis of movement and its free end, said rollers adapted to cooperate with said cams, and means for establishing 30 operative relationship between the free end of the lever and the wagons.

HAROLD H. MIRKIL.
